US0D1005564S

(12) **United States Design Patent** (10) **Patent No.:** **US D1,005,564 S**
(45) **Date of Patent:** **** Nov. 21, 2023**

(54) **SET OF LAMPS**

(71) Applicant: **YIWU PUHONG TRADING CO., LTD**, Yiwu (CN)

(72) Inventor: **Hongxue Zhou**, Linhai (CN)

(73) Assignee: **YIWU PUHONG TRADING CO., LTD**, Yiwu (CN)

(**) Term: **15 Years**

(21) Appl. No.: **29/772,932**

(22) Filed: **Mar. 4, 2021**

Related U.S. Application Data

(62) Division of application No. 29/753,144, filed on Sep. 30, 2020, now Pat. No. Des. 916,334.

(57) **CLAIM**

The ornamental design for a set of lamps, as shown and described.

DESCRIPTION

FIG. 1 is a perspective view of a set of lamps showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the set of lamps where the set of lamps is in a configuration of use.

The lamps are shown with a symbolic break in its length and the appearance of any portion of the set of lamps between the break lines form no part of the claimed design. The broken lines in the drawings depict portions of the set of lamps that form no part of the claimed design.

1 Claim, 9 Drawing Sheets
